MACHINE AND METHOD FOR FORMING
HELICAL SPRINGS

Raymond F. Carlberg, Grand Rapids, Mich.

Application February 11, 1937, Serial No. 125,206

13 Claims. (Cl. 140—103)

The present invention relates to machines and methods for successively forming helical springs with mounting or attaching opposite ends; and its object is, generally, to provide an improved machine and method for thus forming such springs; and more particularly, to provide a continuously operating machine comprising means for bending over, from parallelism with a fed helical spring-work piece, portions thereof to 5 constitute mounting or attaching opposite ends for each of a succession of finished helical springs, means for severing each finished spring from the work piece, and means for limiting the feed movements thereof, said means operating in 10 ordered time relation.

Although such means may be otherwise mounted for operative movement, they are preferably mounted for circuitous movement in one direction.

20 An illustrative preferable embodiment of my invention is illustrated by the accompanying drawings, in which:

Figure 1 is an elevational front view of the machine;

25 Figure 2 is an elevational left-hand side view thereof;

Figure 3 is a vertical sectional view of the same taken on line 3—3 of Figure 1;

Figure 4 is a developed edge view of the rotor disk of the machine.

30 Figure 5 is an outer (left hand) side view of a portion of said disk with a work-bending member mounted thereon;

Figure 6 is a like view of another portion of the disk with the severing member carried thereby;

35 Figure 7 is a like view of another portion of the disk with a work-bending member thereon;

Figure 8 is a sectional view of parts shown in Figure 5 taken on line 8—8 of that view and of Figure 4;

40 Figure 9 is a sectional view of parts seen in Figure 6 taken on line 9—9 of that view and of Figure 4;

Figure 10 is a sectional view of parts shown on Figure 7 taken on line 10—10 of that view and of Figure 4;

45 Figure 11 is a radial sectional view of the rotor disk and of a stop member mounted thereon taken on either line 11—11 of Figure 4;

50 Figure 12 is an inner (right hand) side view of a portion of rotor disk with a work-bending member and finger carried thereby;

Figure 13 is a like view of said portion of the disk and said member in a farther turned position of rotor;

55 Figure 14 is a like view of another portion of the disk with a stop member thereon;

Figure 15 is a like view of another portion of said disk with the severing member thereon;

60 Figure 16 is a radial sectional view of the rotor

disk, a stop member mounted thereon and adjacent parts taken on line 16—16 of Figure 14;

Figure 17 is an inner (right hand) side view of a portion of said disk with a work-bending member carried thereby;

Figure 18 is a sectional view thereof taken on line 18—18 of Figure 17;

Figure 19 is a side view of a finished helical spring.

This machine has the following parts or members. In a horizontal bearing 1 in the standard 10 2 of a suitable base, rotates the shaft 3 of a rotor element driven by a pulley 4 coupled therewith by a suitable clutch, as that shown in Figure 1. This rotor element has a head, or disk 5, on 15 which are carried angularly spaced work-bending members 6, 7, a severing member 8, stop members 9, 10 and a work-bending finger 11, the members 6, 7, 8 being adjustable in radial slots 12 in the disk's outer (left hand) side and held 20 in adjusted position by screws 13 extending through slots 14 in the disk and threaded in said members, and the stop members are adjustably held inwardly from the outer (left hand) side of the disk by screws 15 extending through these 25 members' slots 16 and threaded in the circular edge portion of said disk, all as shown in the views. These stop members are shown adjusted inwardly from the disk's outer side at a distance 30 equal to the thickness of one coil or turn of the helical spring. A cylinder 17 is turnable and slideable in a horizontal bearing 18 through the standard 19 to adjusted position in which it is held by the set screw 20. This cylinder has 35 an eccentric bore 21.

The machine operates as follows: The rotor is turned to the position wherein the work—a length 22 of helical spring—registers with the stop member 9. The work is fed inwardly through the bore 21 until its inner end 23 abuts 40 said stop member as shown in Figure 4. The rotor being turned by the pulley in the direction of the long arrows of Figure 4 and the curved arrows of other views to operate the machine, causes the forward edge 24 of the work-bending member 6 to engage between the first and second turns or coils at the work's inner end 23, and causes said member's curved side 26, to bend over the first (i. e. the end) coil to constitute the mounting part—the eye or hook 27—at one end 45 50 of the finished spring 28 shown in Figure 19. (See Figures 17, 18.)

The work is then fed inwardly until its inner end (said eye 27) abuts the stop 30, adjustable on the rod 31 to provide finished springs of desired length. The disk's continuing rotation brings its finger 11 into engagement with the inwardly protruding portion 33 of the work and springs its coil 34 from the next coil 35 (Figures 1 and 12) so that the forward edge 36 of the 55 60

following work-bending member 7 may readily enter between these two coils and its curved side 37 may bend over the work's portion 33 from coil 35 (Figure 13) which coil 35 is to constitute the eye 35 at the other end of the finished spring. The rotor's continuing rotation brings the other stop member 10 into registration with the work, whereupon the work is fed inwardly a slight distance—the width, of one of its coils—until the 10 coil 35 abuts said stop member. (Figure 16.) The rotor's continuing movement brings the cutting edge 38 of the severing member 8 between coil 35 and the next coil inwardly therefrom, thus severing the finished spring 28 from the remainder of the work (Figure 15). The process of successively forming individual finished springs with mounting portions 27 and 35 at their opposite ends is continued by the constant rotation of the rotor and the feeding of the work as 20 above described.

It will thus be seen that the disk element 5 rotatably moving in a direction transverse that portion 22 of the work which is guided in the bore 21 carries the member for severing from said portion 22 that portion 33 which protrudes from the guide sufficiently to constitute one of the finished springs and also carries the members for bending over end portions of each of said portions 22, 33 which constitute the mounting 30 end parts or eyes 27, 35 of each finished spring. The cylinder 17 may be turned to adjusted positions for increasing or decreasing the distance between its bore 21 and the axis of the rotor thus to adjust the action of the work-bending and severing members relatively to the axis of the helical work; these members may be severally adjusted radially of the disk for similar purpose; and the stop members 9, 10 may be adjusted in the rotor's axial direction to provide spring-mounting 35 portions comprising one or more coils.

It will be seen that there is no waste of the work material in the forming of successive finished springs 28. But if the inner end of the helical work is deformed so that a perfect eye or hook 27 cannot be formed therefrom, the work may be fed a short distance through the bore 21 and the deformed end cut off by the member 8 on rotating the disk slightly. The cylinder 17 may be longitudinally adjusted in its bearing 18 to 50 cause its inner end 40 to properly cooperate with the severing means carried by the rotor disk.

My method of forming such springs appears from the description of the machine whereby said method may be practiced.

The invention being intended to be pointed out in the claims, is not to be limited to or by details of construction and arrangement of the particular embodiment thereof illustrated by the drawings or hereinbefore described.

I claim:

1. A machine of the class described for successively forming helical springs from longitudinally fed helical spring work, comprising: a guide for a portion of the longitudinally fed work; an element having a movement transverse the work; a member carried by said element for severing from said portion a free end portion of the work to constitute one of said helical springs; a member carried by said element for bending over an end part of one of said portions to constitute a mounting part of one of said helical springs.

2. A machine of the class described for successively forming helical springs from longitudinally fed helical spring work, comprising: a guide for a portion of the longitudinally fed work; a rotatable element having a movement transverse the work; a member carried by said element for bending over from said portion a free

end having a movement transverse the work; a member carried by said element for severing from said portion a free end portion of the work to constitute one of said helical springs; members carried by said element for bending over adjacent end parts of said portions respectively to constitute mounting parts of successive helical springs.

3. A machine of the class described for successively forming helical springs from longitudinally fed helical spring work, comprising: a guide for a portion of the longitudinally fed work; a rotatable element having a movement transverse the work; a member carried by said element for severing from said portion a free end portion of the work to constitute one of said helical springs; a member carried by said element for bending over an end part of one of said portions to constitute a mounting part of one of said helical springs.

4. A machine of the class described for successively forming helical springs from longitudinally fed helical spring work, comprising: a guide for a portion of the longitudinally fed work; a rotatable element having a movement transverse the work; a member carried by said element for severing from said portion a free end portion of the work to constitute one of said helical springs; members carried by said element for bending over adjacent end parts of said portions respectively to constitute mounting parts of successive helical springs.

5. A machine of the class described for successively forming helical springs from longitudinally fed helical spring work, comprising: a guide for a portion of the longitudinally fed work; an element having a movement transverse the work; a member carried by said element for bending over from said portion a free end portion of the work protruding from the guide far enough to constitute one of said helical springs; a stop for limiting the feed movement of the first mentioned portion, spaced from the guide a distance equal to a length of the work adapted to constitute a mounting end part of said helical spring; a member carried by said element for severing the second mentioned portion with said length from the first mentioned portion of the work.

6. A machine of the class described for successively forming helical springs from longitudinally fed helical spring work, comprising: a guide for a portion of the longitudinally fed work; an element having a movement transverse the work; a member carried by said element for bending over from said portion a free end portion of the work protruding from the guide far enough to constitute one of said helical springs; a stop for limiting the feed movement of the first mentioned portion, spaced from the guide a distance equal to a length of the work adapted to constitute a mounting end part of said helical spring; a finger carried by said element for engaging said second mentioned portion and springing the same laterally from the first mentioned portion; a member carried by said element for severing the second mentioned portion with said length from the first mentioned portion of the work.

7. A machine of the class described for successively forming helical springs from longitudinally fed helical spring work, comprising: a guide for a portion of the longitudinally fed work; a rotatable element having a movement transverse the work; a member carried by said element for bending over from said portion a free

end portion of the work protruding from the guide far enough to constitute one of said helical springs; a stop for limiting the feed movement of the first mentioned portion, spaced from the 5 guide a distance equal to a length of the work adapted to constitute a mounting end part of said helical spring; a member carried by said element for severing the second mentioned portion with said length from the first mentioned portion of the work.

8. A machine of the class described for successively forming helical springs from longitudinally fed helical spring work, comprising: a guide for a portion of the longitudinally fed work; 15 a rotatable element having a movement transverse the work; a member carried by said element for bending over from said portion a free end portion of the work protruding from the guide far enough to constitute one of said helical springs; a stop for limiting the feed movement of the first mentioned portion, spaced from the 20 guide a distance equal to a length of the work adapted to constitute a mounting end part of said helical spring; a finger carried by said element for engaging said second mentioned portion and springing the same laterally from the first mentioned portion; a member carried by said element for severing the second mentioned portion with said length from the first mentioned 25 portion of the work.

9. A machine of the class described for successively forming helical springs from longitudinally fed helical spring work, comprising: a guide for a portion of the longitudinally fed work; 30 an element having a movement transverse the work; a stop for limiting the feed movement of the work, spaced from the guide a distance equal to a length of the work adapted to constitute a mounting part of one of said helical springs at one end thereof; a member carried by said element for bending over said length from said portion of the work to constitute said mounting part; a member carried by said element for bending over from said portion a free end portion of the 35 work fed to a position protruding from the guide far enough to constitute said helical spring; a stop for limiting the feed movement of the first mentioned portion, spaced from the guide a distance equal to a length of the work, adapted to 40 constitute a mounting part of said helical spring at the opposite end thereof; a member carried by said element for severing the second mentioned portion with said lengths from the first mentioned portion of the work guided in the 45 guide.

10. A machine of the class described for successively forming helical springs from longitudinally fed helical spring work, comprising: a guide for a portion of the longitudinally fed work; an 50 element having a movement transverse the work; a stop for limiting the feed movement of the work, spaced from the guide a distance equal to a length of the work adapted to constitute a mounting part of one of said helical springs at one end thereof; a member carried by said element for bending over said length from said portion of the work to constitute said mounting part; a member carried by said element for bending over from said portion a free end portion of the work fed to a position protruding from the guide far enough to constitute said helical spring; a stop for limiting the feed movement of the first 55

mentioned portion, spaced from the guide a distance equal to a length of the work adapted to constitute a mounting part of said helical spring at the opposite end thereof; a finger carried by said element for engaging the protruding second 60 mentioned portion and springing the same laterally from the first mentioned portion of the work guided in the guide; a member carried by said element for severing the second mentioned portion with said lengths from the first 65 mentioned portion of the work guided in the guide.

11. A machine of the class described for successively forming helical springs from longitudinally fed helical spring work, comprising: a guide 15 for a portion of the longitudinally fed work, an element rotatable transversely of the work carrying the following members in angularly spaced successively operating relation; a stop for limiting the feed movement of the work, spaced from 20 the end of the guide a distance equal to a length of the work adapted to constitute a mounting part of one of said helical springs at one of its ends; a member for bending over said length from the portion of the work guided in the guide 25 to constitute said mounting part; a member for bending over from said portion guided in the guide a free end portion of the work fed to a position protruding from the guide far enough to constitute said helical spring; a stop for limiting 30 the farther feed movement of the first mentioned portion guided in the guide, spaced from the end of the guide a distance equal to a length of the work adapted to constitute a mounting part of said helical spring at its other end; and 35 a member cooperating with the end of the guide for severing the protruding second mentioned portion including both its said mounting opposite end parts from the remainder of the first mentioned portion of the work guided in the 40 guide.

12. A machine of the class described for successively forming helical springs from longitudinally fed helical spring work, comprising: a base, a cylindrical guide turnably mounted on 45 the base, having an eccentric bore for guiding the feeding movement of the work therethrough; an element having a movement on the base transverse the fed movement of the work; a member carried by said element for severing a portion of 50 the work protruding from the end of the guide, the guide being turnable for adjusting the distance between its bore and the line of said element's movement.

13. A method of forming helical springs with 55 mounting parts at their opposite ends, which method includes the following acts performed in the following order: axially moving a helical spring workpiece through a guide to a stopped position; bending over the forward end portion of 60 the workpiece protruding from the guide to constitute a mounting part of a helical spring at one end thereof; axially moving the workpiece farther through the guide a distance equal to the desired length of the helical spring; bending 65 over this protruding portion of the workpiece to constitute a mounting part of said helical spring at the other end thereof; and severing said protruding portion with said mounting parts at its opposite ends from the remainder of 70 the workpiece.

RAYMOND F. CARLBERG.
